UNITED STATES PATENT OFFICE.

FRED WILLIAM VOGEL, OF SACRAMENTO, CALIFORNIA.

SAFETY LIGHT.

Application filed October 15, 1926. Serial No. 141,853.

The object of this invention is to produce an article adapted to be readily carried in the pocket of the user, and by means of which a light may be provided for lighting 5 a cigar, cigarette, or some forms of illuminating devices, the article being especially designed for convenience and safety.

A further object is to produce a device of the character indicated, which shall include 10 a casing having a circular chamber in which a paper strip is installed, this strip projecting thru a feed channel, toward an opening adapted to be closed by a cover,—means being employed for feeding the strip when 15 a slideable device is manually operated, this device serving also to open the cover for the side of the casing,—the strip being provided with heads or percussion devices adapted to ignite upon engaging a prepared surface.

20 A further object is to provide a strip carrying portions to be ignited by frictional contact, the edges of the strip being slotted, and adapted for engagement by a particular form of feeding device carried by a slide- 25 able element adapted to control a cover for an opening in the casing of the article, thru which the end of the strip is fed, in connection with the operation resulting in ignition, for the purpose indicated.

30 With the foregoing and other objects in view, the invention consists in the novel construction and arrangement of elements described, illustrated and claimed, it being understood that modifications may be made 35 within the scope of the claims without departing from the spirit of the invention.

In the drawings forming part of this application,

40 Figure 1 is a view of the device in elevation.

Figure 2 is a view in elevation with the slideable member in the position assumed when the strip is fed to operative position.

45 Figure 3 is a view of the device in vertical section.

Figure 4 is also in vertical section, and shows the cover in open position, having been thrown to this position by the operation of the slide of Figures 1, 2 and 6.

50 Figure 5 is a section on line 5—5 of Figure 1.

Figure 6 is a perspective view of the slideable element serving to open the cover and to advance the strip carrying the elements to be ignited.

55 Figure 7 is a perspective view of a clip

or the like designed to carry prepared material serving to ignite the heads carried by the paper strip.

Figure 8 shows a fragment of the paper strip, the latter being slotted on opposite edges, and carrying the heads referred to above.

Figure 9 is a detail view of the cover and elements connected therewith.

The casing includes an upper portion 10, side or edge portions 11 and 12, and front and back members 13 and 14. The lower edge portion 15 is of partly circular form as illustrated, and a chamber 16 is provided 70 within the lower portion of the casing, as the device is illustrated in the drawings, this chamber being approximately circular but including a throat portion 18, the walls of which merge into the walls 20 of the feed channel, thru which the strip to be fed and ignited, passes.

The flanges 14' on the edge of element 14 are deflected inwardly, as illustrated in Figure 5, and engage the grooves 12' on the 80 edge walls 11 and 12,—this construction permitting of the connection of the cover or plate 14 with the remainder of the casing, without the necessity of employing other securing devices.

A cover 22 is pivotally mounted at 22' on the casing and closes an opening in the edge wall of the casing and also closes the feed channel. This cover is provided with a curved and forked end portion 24 acting as 90 a strip severing device, so that a used portion of the paper strip of Figure 8 may be separated from the remaining portion, after the cigar or cigarette has been lighted, or after any other similar purpose has been 95 effected.

The paper strip 30 is coiled within chamber 16 and is provided with heads or enlargements 31, corresponding substantially with match heads, and the slots 32 are so positioned that the feeding device referred to below engages these slots after feeding a predetermined length of the strip including one head 31.

The feeding device of Figure 6 and elsewhere includes an arm 33 having an end 33' for pivotal connection with the cover 22, and this arm includes a portion 34 bearing on the surface of the casing, and a portion 35 extending through a slot in the casing, shown in Figure 2, this portion carrying a U-element including fingers 36 movable be-

tween the walls 20 of the channel portion, and tongues 37 for engagement with the slotted portions 32 of the strip, so that the latter may be fed to the position required for igniting one of the heads 31.

The strip feeding device is operated by pressure applied at 34, by the thumb or finger of the user, who first releases latch 38 rigid with cover 22 and having a notched end 38' engaging offset or shoulder 34' of member 34. The thumb nail is applied to the deflected edge 38'' for the releasing operation.

Assuming that this match releasing operation has taken place, pressure at 34 opens cover 22 and feeds the strip, causing the ignition of one of the match heads 31, which engages prepared surface 42 carried by extension 41 of clip 40. Spring 44 prevents accidental movement of the strip after feeding. The match head being ignited and the light employed for the purpose desired, the cover 22 is closed and the used portion of strip 30 is severed by the device 24. The closing of the cover causes the notched end 38' to automatically engage at the point 34', thereby retaining the cover.

The used strip may be discarded or deposited in the chamber within the upper portion of the casing, which may also be employed at times for receiving ashes. When a new strip 30 is inserted in the casing, the ignition device of Figure 7 may be replaced by another similar element having a prepared surface in good condition in order to insure the lighting of the match head upon the operation of the element 33 in the manner specified.

The wall 14 of the casing is slidable with reference to the edge walls 11 and 12, so that access may readily be obtained to the interior, for the purposes indicated.

Having described the invention, what is claimed is:

1. In a device of the class described, a casing including walls defining chambers,

one of which forms a magazine, walls defining a channel extending from the chamber last named toward the outer portion of the casing, means for feeding a strip carrying elements to be ignited through the channel, means for frictionally engaging the elements on the strip thus fed, and a pivoted cover mounted on the casing and controlled by the direct mechanical thrust of the feeding means, said cover being adapted to close the outer end of the channel. 50

2. In a device of the class described, a casing including a chamber for receiving a strip carrying elements to be ignited, the casing having a channel opening through the edge of said casing and having communication with the chamber, a pivoted cover for closing the outer portion of the channel, an operating arm connected with the cover, 60 and opening said cover by direct mechanical thrust and a strip feeding device carried by said arm. 65

3. In a device of the class described, a casing having a chamber therein and having a channel extending from said chamber to the outer portion of the casing, a pivoted cover for closing the outer portion of the channel, an operating arm for imparting direct opening thrust to the cover, a strip feeding device carried by the arm, means for igniting an element to be carried by a strip fed from the chamber, and means for retaining the operating arm in position for holding the cover closed. 70 75

4. In a device of the class described, a casing, means therein defining a chamber for a paper strip carrying match heads, and defining a channel extending from said chamber to the outer portion of the casing, 80 a cover for closing the outer end of the channel, an operating device connected with the cover, a strip feeding device connected with the operating device, and a strip severing device carried by said cover. 85 90

In testimony whereof I affix my signature.

FRED WILLIAM VOGEL.
